UNITED STATES PATENT OFFICE.

GUSTAV A. WENDT, OF CINCINNATI, OHIO.

DESIGN FOR A SMOKER'S STAND.

Application filed September 16, 1926. Serial No. 19,085. Term of patent 3½ years.

To all whom it may concern:

Be it known that I, GUSTAV A. WENDT, a citizen of the United States, residing at Cincinnati, in the county of Hamilton and State of Ohio, have invented a new, original, and ornamental Design for a Smoker's Stand, of which the following is a specification, reference being had to the accompanying drawing, forming part thereof.

I claim:

The ornamental design for a smoker's stand as shown.

GUSTAV A. WENDT.
